UNITED STATES PATENT OFFICE.

THOMAS C. SHEEHAN, OF JERSEY CITY, NEW JERSEY, ASSIGNOR, BY MESNE ASSIGNMENTS, TO AUTOMATIC FURNACE COMPANY, OF NEW YORK, N. Y., A CORPORATION OF NEW YORK.

MELTING AND CASTING POT.

1,074,901.

Specification of Letters Patent.

Patented Oct. 7, 1913.

Original application filed December 7, 1906, Serial No. 346,749. Divided and this application filed March 8, 1907, Serial No. 361,271. Renewed March 20, 1918. Serial No. 755,780.

To all whom it may concern:

Be it known that I, THOMAS C. SHEEHAN, a citizen of the United States, residing at Jersey City, in the county of Hudson and 5 State of New Jersey, have invented a new and useful Melting and Casting Pot, of which the following is a specification:

This invention relates to a casting apparatus for casting slugs or pigs adapted to be 10 employed in linotype or monotype casting machines and the like.

The principal objects of the invention are to provide efficient and convenient means for drawing away the products of combustion and the gases from the molten metal, for stirring or puddling the molten metal when desired, for drawing off the metal from the pot in the desired quantities, and generally to improve and simplify apparatus 20 of this character.

Reference is to be had to the accompanying drawings for a representation of one embodiment of this invention, in which,

Figure 1 is a front elevation thereof, and 25 Fig. 2 is a central vertical sectional view of a portion of the apparatus showing the pot itself on an enlarged scale.

This is a division of my application for patent filed December 7, 1906, Serial No. 30 346,749.

The melting pot 25 is of a substantially hemi-spherical shape that is well known in apparatus of this kind and is provided with a flange 160 at the top, which rests on the 35 top of a supporting casing 12. The pot is provided with an outlet opening 26 to a pouring spout 27. This opening is in the form of a depression from the lowest point of the pot and as all sides of the pot slant 40 down toward it, it will be seen that it is adapted to receive every particle of metal which may be melted in the pot. The opening 26 terminates in a flange 28 against which is located a pouring valve seat 29 45 separated from the flange, and from the pouring spout 27, by sheets of asbestos 17 and detachably secured to the flange by bolts 18 or the like, passing through the body of the pouring spout itself. The pouring 50 spout is provided with an inclined outlet 30 which is at all points lower than the opening 26 in the melting pot and consequently is well adapted to drain all metal therefrom. Normally seated against the

valve seat is a valve 31 mounted on a stem 55 32 provided with screw-threads 33. This stem is reduced at the end and extends through a bearing in the pouring spout. It is provided with an arm 34 fixed to its end, this arm being provided with means for 60 preventing the valve stem from turning. This means is shown in the form of a pin 35 parallel with the stem and reciprocating in an opening in the pouring spout. In order to provide for manipulating the valve so as 65 to move it toward and from its seat, a nut 36 is mounted on the screw-threaded portion thereof and this nut is provided with a handle 37. The nut 36 is located in a space 38 in the body of the pouring valve casing and 70 as this space is substantially the same length as the nut, the latter cannot move longitudinally; its oscillation having the effect of moving the valve back and forth to and from its seat.

In Fig. 1 is shown a hood 40 adapted to be placed on the top of the melting pot flange to receive the gases given off from the molten metal and connected if desired with a draft pipe 41. The products of combustion from 80 the gas flame are led through a pipe 42 to the draft pipe. The hood is preferably provided with a door 43 through which access may be had to a stirring or puddling device 44 located in the melting pot. This device 85 consists of a bow-shaped frame having openings therein through which the metal may pass and pivoted on bearings 45 located on the flange 160 or in any other convenient position. This puddler partakes of the 90 shape of the pot, the bottom of which is preferably hemi-spherical. Therefore, the puddler can be of semi-circular shape having its bearings at the center of the circle and can be rocked on the bearings by means of 95 a handle 46 so as to pass over the bottom surface of the pot, and not only puddle and agitate the metal, but if necessary, scrape any adhering particles from the inside surface of the pot.

From the above description, it will be obvious how the puddler is used and also how the metal is discharged from the melting pot.

By the construction of the casting apparatus on the principles set forth above, 105 whether in the exact form illustrated or not, but within the scope of the claims, it will be seen that a melting pot is provided which

will melt all the metal placed in it and discharge it all through the spout. Furthermore, the pouring valve is efficiently operated in a most simple manner; also the 5 products of combustion and waste gases from the molten metal are easily and efficiently withdrawn; the puddling of the metal is efficiently provided for by the puddler and the casting of the same is readily 10 and quickly accomplished in any mold that it may be desired to use.

While I have illustrated and described a particular form in which my invention may be embodied, I am aware that many modifications 15 may be made therein by an person skilled in the art within the scope of the claims. Therefore, I do not wish to be limited to the particular construction shown and described, but

20 What I do claim is:—

1. A melting pot comprising a hemispherical bottom and an open top having an outwardly extending top flange, and provided with a mixing or puddling device consisting 25 of a semicircular metallic strip having transverse perforations and substantially fitting said bottom, and provided with outwardly extending pivots at the top resting on said flange, and a handle projecting up from one 30 of the pivots.

2. In a casting apparatus, the combination of a melting pot having a depressed outlet trough, a valve seat movably mounted adjacent to the mouth of said trough, a pouring 35 spout mounted on the valve seat, and means for detachably securing the spout and seat on the mouth of the pot.

3. In a casting apparatus, the combination of a melting pot having a depressed out-

let trough, a valve seat movably mounted 40 adjacent to the mouth of said trough, a pouring spout mounted on the valve seat, means for detachably securing the spout and seat on the mouth of the pot, and heat resisting packings located between the valve 45 seat and the mouth of the trough on one side and the pouring spout on the other.

4. In a casting apparatus, the combination of a melting pot having a depressed outlet trough, a valve seat, a valve for said seat, the stem of said valve having a screw-thread, means for preventing the valve from turning, and a nut for said screw-thread.

5. In a casting apparatus, the combination of a melting pot having a depressed outlet trough, a valve seat, a valve for said seat, the stem of said valve having a screw-thread, 55 means for preventing the valve from turning, a nut for said screw-thread, a handle for operating said nut, and means for prevent- 60 ing longitudinal motion of the nut.

6. In a casting apparatus, the combination of a melting pot, a valve seat therefor, a pouring spout, a valve having a screw-threaded stem and provided with a pin parallel to said stem, said pouring spout having a socket for said pin to prevent the stem from turning, said pouring spout also having a recess, a nut located in said recess and fitting the thread on the valve, and means 70 for turning said nut.

In testimony whereof I have hereunto set my hand, in the presence of two subscribing witnesses.

THOMAS C. SHEEHAN.
